FLUID PRESSURE CONTROL VALVE FOR AUTOMOTIVE HEATERS

Walter R. Armand, 1320 Speer Blvd.,
Denver, Colo. 80204

Filed Feb. 27, 1969, Ser. No. 15,953

Term of patent 14 years

Int. Cl. D23—01

U.S. Cl. D23—21

FIG. 1

FIG. 2

FIG. 1 is a side view of a fluid pressure control valve for automotive heaters showing my new design; and
FIG. 2 is an end view thereof.

The opposite side and the opposite end are similar in appearance, respectively, to the side and end illustrated.

I claim:

The ornamental design for a fluid pressure control valve for automotive heaters, as shown and described.
